AMPHIBIAN PROPULSION MECHANISM

James M. Hait, San Gabriel, Calif., assignor to
Food Machinery Corporation, San Jose, Calif.,
a corporation of Delaware

Application January 8, 1942, Serial No. 426,032

5 Claims. (Cl. 305—10)

This invention relates to amphibian craft and particularly to propulsion mechanism functioning to support and propel said craft when traveling on land and to propel said craft through the water when it is afloat.

It is customary in military tank construction to propel these with a track laying mechanism including a track forming chain or belt, which for convenience will hereinafter be referred to by the generic term "traction belt." In seeking to adapt this belt for use by amphibians it has been found that amphibian grousers, to have maximum hydrodynamic efficiency, need to be spaced on centers which leaves intervening portions of the belt inadequately supported.

It is an object of this invention to provide an amphibian propulsion mechanism in which the aforesaid belt is utilized and yet adequate support is given to all portions of the belt.

The manner of accomplishing the foregoing object, as well as further objects and advantages, will be made manifest in the following description taken in connection with the accompanying drawing, in which:

Fig. 1 is a fragmentary side elevational view of a preferred embodiment of the invention.

Fig. 2 is a bottom plan view of Fig. 1.

Fig. 3 is a cross-sectional view taken on the line 3—3 of Fig. 1.

Referring specifically to the drawing, the propulsion mechanism 10 disclosed therein includes an endless traction belt 11 which is adapted to be supported for endless movement on an amphibian craft, the latter having bogie wheels 12 which ride on the belt so as to support the craft when it is traveling on land.

The belt 11 includes two endless tracks 13 formed of rubber, two series of endless cables 14, two endless series of clamps 15, said cables and clamps being imbedded in the rubber tracks 13 and being united by stud bolts 16 and 17. The latter bolts also extend through and bind an endless series of guide members 18 to the clamps 15. The stud bolts 16 and 17 have alternate clamps 15 provided on base plates 20 of grousers 21 and the balance of the stud bolts are mounted on intermediate plates 22.

As clearly shown in Fig. 1, the base plates 20 have downwardly bent end portions forming lips 25 to accommodate the intermediate plates 22. While the grousers 21 are preferably made of steel, the intermediate plates 22 may be of aluminum to save weight.

Each of the grousers 21 includes an impeller blade 30 formed integral with the base plate 20

and shaped so as to not only give a maximum efficiency when the amphibian is afloat to provide propulsive thrust for impelling the craft through the water, but also to provide a rigid support for the belt 11 and the amphibian when the latter is traveling on land.

The weight of the amphibian equipped with the mechanisms 10 is carried on the bogie wheels 12 during land travel, these wheels in turn resting on the tracks 13. When one of these wheels is disposed in between an adjacent pair of the grousers 21, it depresses the tracks 13 so as to bring the intermediate plate 22 therebeneath into contact with the adjacent lips 25 of adjacent grousers 21.

When not directly beneath one of the bogie wheels 12, each of the plates 21 is lifted by the belt 11, expanding to its normal position, thereby leaving adequate free space between this plate 22 and the adjacent lips 25 to allow articulation when the belt 11 passes through an angle as when traveling past the leading bogie wheel 12.

The term "rubber" as used herein and in the claims is to be understood as including not only that material chemically known as rubber, but also all suitable equivalents therefor.

What I claim is:

1. In an amphibian propulsion mechanism, the combination of: an endless traction belt; bogie wheel means rolling on said belt and supporting said amphibian; an endless series of grousers secured to said belt in spaced relation with each other; and an endless series of intermediate plates secured to said belt and having their opposite edges overlapping adjacent edges of said grousers, said grousers and plates thus cooperating to support said belt to provide a continuous and substantially smooth track for said amphibian to ride upon when traveling on land.

2. In an amphibian propulsion mechanism, the combination of: an endless belt including an endless rubber track means, endless cable reinforcements imbedded therein, an endless series of clamps clamping certain cables and imbedded in said track means; bogie wheel means rolling on said belt and supporting said amphibian; an endless series of grousers secured to alternate clamps; and an endless series of intermediate plates secured to the balance of said clamps, said intermediate plates overlapping adjacent grousers, said grousers and plates thus cooperating to support said belt to provide a continuous and substantially smooth track for said amphibian to ride upon when traveling on land.

3. A combination as in claim 2 in which de-

pressed lips are formed on edge portions of said grousers to accommodate edges of an adjacent intermediate plate.

4. A combination as in claim 2 in which depressed lips are formed on edge portions of said grousers to accommodate edges of an adjacent intermediate plate, there normally being free spaces between said intermediate plates and said lips to permit articulation of said grousers and said plates when said belt passes around a turn.

5. In an amphibian propulsion mechanism, the combination of: an endless traction belt; bogie

wheel means rolling on said belt and supporting said amphibian; an endless series of grousers secured to said belt in spaced relation with each other; and an endless series of intermediate plates secured to said belt and having their opposite edges overlapping adjacent edges of said grousers, said grouser edges being recessed to receive said plate edges so that said grousers and plates unite to support said belt to form a substantially smooth track for said amphibian to ride upon when traveling on land.

JAMES M. HAIT.
